HIGH-SPEED BOLT DIESTOCK

Ira Whitfield, Boston, Mass.

Application September 7, 1942, Serial No. 457,608

4 Claims. (Cl. 10—126)

The invention relates to improvements in die stocks, and more particularly to a high speed, self-oiling die stock for threading pipes, rods, and the like, and the primary object of the invention is to provide a more efficient and practical device of this character which substantially reduces the amount of labor required while speeding up the work.

Other important objects and advantages of the invention will be apparent from a reading of the following description taken in connection with the appended drawings, wherein for purposes of illustration a preferred embodiment of the invention is shown.

In the drawings:

Figure 1 is a fragmentary front elevational view of the embodiment.

Figure 2 is a top plan view of Figure 1.

Figure 3 is a fragmentary enlarged transverse sectional view taken through Figure 1 along the line 3—3 and looking downwardly in the direction of the arrows.

Figure 4 is an enlarged transverse vertical sectional view taken through Figure 1 along the line 4—4 and looking toward the left in the direction of the arrows.

Figure 5 is an enlarged fragmentary transverse sectional view taken through Figure 2 along the line 5—5 and looking in the direction of the arrows.

Figure 6 is an enlarged side elevational view of one of the oil pumps.

Figure 7 is a transverse vertical sectional view taken through Figure 6 along the line 7—7 and looking in the direction of the arrows.

Referring in detail to the drawings, the numeral 5 generally designates the main body of the die stock, which has a generally conventional elongated form including tapered sockets 6 and 7 at its opposite ends in which the pipe handles 8 and 9 are threaded. The bore 10 of the socket 6 has communication with the hollow interior oil reservoir 11, with a screen 12 mounted at the point of communication, and the end of the pipe 8 is closed as indicated by the numeral 13, thereby forming a stopper for the filling opening defined by the bore 10 of the socket 6. The bore of the socket 7 is closed off at its inner end by the wall 14, the only path of escape of the oil from the reservoir 11 being through the oil feeders to be described, except when the stopper pipe 8 is withdrawn to open position.

A hollow cylindrical portion 15 extends across the middle and center of the body 5 from side to side, and a guide ring 16 having the grooved

periphery 17 is mounted in one end of the bore 18 of the cylindrical part 15, the guide ring 16 being held in place by radial contact by the inner end of a bolt 19 which is threaded through the wall of the body 5 as indicated in Figure 5 of the drawings.

On the opposite face of the body 5 are supported the die plates 19 and 21 which are similar in formation and arrangement and are of the generally conventional type, the same being slideable toward and away from each other in a longitudinal channel 22 formed in the side of the body 5, the plates having elongated slots 23 through which pass studs 24 threaded in the side of the body 5 and provided with washers 25 which are clampable against the outside of the plates by the bolts 26 in a well known manner to maintain adjusted positions of the plates. Feed bolts 27 working in blocks 28 on the side of the body 5 are used to adjust the plates 20 and 21 toward and away from each other. The cutting teeth 29 arranged in pairs on the opposite horns of the apertures 30 in the inner ends of the plates are fed with oil in accordance with the present invention by small tubes 31 provided at longitudinal intervals with small openings 32 and extending in notches 33 formed in the openings 30 as indicated in the drawings.

The oil feed tubes 31 extend close to the sides 30 of the bore 18 of the cylindrical part 15 and have longitudinally outwardly directed portions 34 which are threaded in the opposite sides of the cylindrical portion 15 and have communication with the longitudinally inward ends of the oil pumps 35 and 36 which have internally restricted end portions 37 threaded in the side wall of the cylindrical portion 15 in communication with the oil feed tubes as clearly shown in Figure 3 of the drawings. The center opening 16' of the guide ring 16 is axially aligned with the center of the space between the said cutting teeth 29, as required for accurate and uniform work.

Each oil pump comprises an elongated tube having a relatively short imperforate portion 38 and a relatively long circumferentially slotted portion 39 whose slots are in communication with the oil reservoir 11. The outer end of the slotted portion 39 terminates in a funnel portion 40 which has at its wide end a convex closure wall 41. Within the pumps are free steel balls 42. Oil entering through the slots in the pump on the reservoir 11 is forced in a radially inward direction through the imperforate portion 38 into the corresponding feed tube 31 as the corresponding side of the die stock is elevated and the cor-

responding ball 42 falls by gravity through the pump, so that oil is fed from the small openings 32 in the oil feed tube to the region of the cutters 29, whereby the region of the cut being made on the rod or pipe is kept cooler and the operation of cutting threads thereon is speeded up, whereby the cutting is facilitated and greater ease in operating the die stock as a whole is procured due to reduction of heat and friction.

In one side of the body 5 in laterally spaced relation to the cylindrical portion 15 is an air tube and trap 43 which has a straight portion traversing the wall of the body 5 as indicated in Figure 5 of the drawings and communicating with the outside atmosphere, the said straight portion extending across the reservoir 11 to a point on the opposite side of the pump 35 where it is curvedly bent as indicated by the numeral 44 in a radially inward direction with respect to the cylindrical portion 15, whence it is bent in a semi-circular form as indicated by the numeral 45 in the opposite direction. The tube 43 is curved and gauged inside to predetermine the amount of outside air which it will admit into the reservoir 11, so that oil can be fed from the reservoir 11 through the feed tubes 31 without inhibition by vacuum within the reservoir which would otherwise obtain. The tube 43 is so arranged that in the ordinary operation of the die stock no oil from the reservoir 11 can escape through the tube 43.

In accordance with the present invention the pipe 9 instead of being the straight usual type has a laterally deflected crank portion 46 on which a suitable handle 47 is mounted. The worker can grasp the handle 47 and literally spin the die stock on the work 48, making complete revolutions without any necessity of changing hands from one pipe 8 to the other pipe 9, and vice versa, as is now necessary in the operation of die stocks, thereby greatly speeding up the work. Such high speed operation of the die stock is made possible by the lubrication supplied by the oil feed arrangement described.

Although there is shown and described herein a preferred embodiment of the invention, it is to be definitely understood that I do not desire to limit the application of the invention thereto except as may be required by the scope of the subjoined claims.

Having described the invention, what is claimed as new is:

1. A high speed die stock comprising a hollow elongated body composing an oil reservoir, a transverse tubular portion extending across said body and opening at its opposite ends through the opposite sides of said body, a work guide on said body at one end of said tubular portion and plates having thread cutting teeth on said body at the opposite end of said tubular portion, oil feed tubes extending along the interior of said tubular portion and reaching the region of the thread cutting teeth, and pumps radiating from said tubular portion and having communication at their inward ends with said oil feed tubes, said pumps having gravity operated elements effective upon rotation of the die stock on the work

to force oil from the reservoir into said oil feed tubes and onto the thread cutting teeth.

2. A high speed die stock comprising a hollow elongated body composing an oil reservoir, a transverse tubular portion extending across said body and opening at its opposite ends through the opposite sides of said body, a work guide on said body at one end of said tubular portion and plates having thread cutting teeth on said body at the opposite end of said tubular portion, oil feed tubes extending along the interior of said tubular portion and reaching the region of the thread cutting teeth, and pumps radiating from said tubular portion and having communication at their inward ends with said oil feed tubes, said pumps having gravity operated elements effective upon rotation of the die stock on the work to force oil from the reservoir into said oil feed tubes and onto the thread cutting teeth, and air inlet means for said reservoir for admitting air to displace oil pumped from the reservoir.

3. A high speed die stock comprising a hollow elongated body composing an oil reservoir, a transverse tubular portion extending across said body and opening at its opposite ends through the opposite sides of said body, a work guide on said body at one end of said tubular portion and plates having thread cutting teeth on said body at the opposite end of said tubular portion, oil feed tubes extending along the interior of said tubular portion and reaching the region of the thread cutting teeth, and pumps radiating from said tubular portion and having communication at their inward ends with said oil feed tubes, said pumps having gravity operated elements effective upon rotation of the die stock on the work to force oil from the reservoir into said oil feed tubes and onto the thread cutting teeth, said pumps each comprising a tube having an imperforate portion communicating with a corresponding oil feed tube and an apertured portion, and a gravity operated element free within the tube.

4. A high speed die stock comprising a hollow elongated body composing an oil reservoir, a transverse tubular portion extending across said body and opening at its opposite ends through the opposite sides of said body, a work guide on said body at one end of said tubular portion and plates having thread cutting teeth on said body at the opposite end of said tubular portion, oil feed tubes extending along the interior of said tubular portion and reaching the region of the thread cutting teeth, and pumps radiating from said tubular portion and having communication at their inward ends with said oil feed tubes, said pumps having gravity operated elements effective upon rotation of the die stock on the work to force oil from the reservoir into said oil feed tubes and onto the thread cutting teeth, handles connected to the opposite ends of said body and extending in longitudinal alignment therewith, at least one of said handles having a laterally directed crank handle facilitating rotation of the die stock on the work with one hand on said crank handle.

IRA WHITFIELD.
